United States Patent Office.

JOHN C. JEWETT, OF BUFFALO, NEW YORK.

Letters Patent No. 60,738; dated January 1, 1867.

IMPROVED SLOP JAR.

The Schedule referred to in these Letters Patent and making part of the same.

TO ALL WHOM IT MAY CONCERN:

Be it known that I, JOHN C. JEWETT, of the city of Buffalo, in the county of Erie, and State of New York, have invented certain new and useful improvements in the mode of constructing Slop Jars; and I do hereby declare that the following is a full and exact description thereof, reference being had to the accompanying drawings, making part of this specification, in which—

Figure 1 is a vertical section; and

Figure 2 a top view of a jar of my improved construction.

Like letters indicate corresponding parts in both drawings.

The nature of my improvements consists in the construction of the cover with a lip turning vertically downward from the periphery thereof, so that its edge is immersed in an annular reservoir of water formed around the body of the jar, in combination with a central trap at the induction orifice of the cover, both so arranged that, in pouring water into the jar without removing the cover, the central trap, and also the annular reservoir become filled, and prevent the escape of all effluvia from the vessel.

As represented in the drawings, A is the body of the jar, B the cover, and C a flaring rim, starting from the outside a little below the top edge of the jar, so as to leave an annular space around the top for retaining water. The cover B is concave on its top, so that it will drain toward the centre, but the outer edge is provided with a flange, e, bent downward in a vertical position, or nearly so. The circumference of this flange is such as to allow it to pass easy over the top edge, f, of the jar, and the acute angle formed between the flange e and the inclined sides of the top, constitute a seat for the edge f to rest upon and hold the cover so that it is not likely to be accidentally displaced. The pouring of water from another vessel on the cover occasions an overflow before it can pass through the central orifice, sufficient to fill the annular recess between the rim C, and sides f, and the flange e, being immersed, makes the joint between the sides and cover hermetical, so that no effluvia can escape from the interior by that passage. The central aperture, D, of the cover is also formed with a vertical tube or funnel, h h, which directs the water into a suspended cup, E, below, the top edge of which is higher than the termination of the funnel h h, so that the latter will always be slightly immersed in the liquid contained in the cup E, and in like manner prevent the escape of any effluvia arising from the contents of the vessel. A cap or guard, G, is placed over the aperture D, for the double purpose of preventing the water from dashing directly into cup E, and by its force partially expelling the portion designed to be retained by the latter, and to form a knob or handle for the removal of the cover when required to empty the jar. Metallic jars acquire, from use, an offensive odor when entirely empty, and the provision here made renders that odor undiscernible by the simple precaution of pouring a little pure water on the cover when it is to remain empty or unused.

What I claim as my invention, and desire to secure by Letters Patent, is—

A slop jar provided with the annular water recess formed between the sides f f and rim C, submerged flange e e and central odor trap of the concave cover B, constructed and arranged substantially as and for the purposes set forth.

In witness whereof I have hereunto signed my name in the presence of two subscribing witnesses,
